UNITED STATES PATENT OFFICE

133,850

DESIGN FOR A PORTABLE CONTAINER FOR LIQUIDS

David T. Clements, United States Army, Arlington, Va., and John M. Kenderdine, United States Army, Silver Spring, Md.

Application July 28, 1942, Serial No. 107,730

Term of patent 3½ years

To all whom it may concern:

Be it known that we, Major David T. Clements and Captain John M. Kenderdine, United States Army, citizens of the United States, residing at Arlington, Virginia, and Silver Spring, Maryland, respectively, have invented a new, original, and ornamental Design for a Portable Container for Liquids, of which the following is a specification, reference being had to the accompanying drawings, forming part thereof.

Fig. 1 is a side elevational view of a portable container for liquids, showing our new design,

Fig. 2 is a front elevational view,
Fig. 3 is a plan view,
Fig. 4 is a side elevational view, showing the side opposite that shown in Fig. 1, and
Fig. 5 is a rear elevational view thereof.

We claim:

The ornamental design for a portable container for liquids, as shown.

DAVID T. CLEMENTS.
JOHN M. KENDERDINE.
